TYPEWRITING MACHINE

Jesse A. B. Smith, Stamford, Conn., assignor to
Underwood Elliott Fisher Company, New York,
N. Y., a corporation of Delaware

Application October 27, 1928, Serial No. 315,548
Renewed December 13, 1933

12 Claims. (Cl. 197—126)

The present invention relates to manifolding upon multiple-ply form-printed paper-webs, and more particularly to mechanism for doing this kind of work wherein interleaved carbon-sheets 5 are shifted from a typed set of forms to the next untyped forms.

In the patent to Crews, 1,565,550, of December 15, 1925, is disclosed flexible means for fastening carbon-sheets together as a unit for riding 10 through the typewriting machine with the web; the carbon-sheets being occasionally held back in order to permit the web-plies to be stripped or drawn through the interleaved carbon-sheets, to bring the latter into manifolding relation with 15 said next untyped forms.

According to the present invention improved means is provided whereby an assemblage of carbon-sheets interleaved between plies of work-web may be fed therewith through the machine 20 as a form is typed, and thereafter may be held stationary at the delivery side of the platen, said holding means permitting independent advance of the web-plies, for stripping the carbon-sheets to the next set of untyped forms.

According to one way of practicing the present invention, there are interleaved between the plies of a multiple-ply work-web loose carbon-sheets each of which preferably has tablike lateral extensions, adjacent its trailing edge, which 25 may protrude from the opposite sides of the work-web. Side-edge-guiding means form a chute for the work-web at the introductory and delivery sides of the platen. A lateral guide-chute is preferably provided for the carbon-sheet 30 extensions. A clamp is disposed at each side of the work-web, but clear thereof, for gripping the carbon-sheet projections against the floor of the chute. While the clamps are effective, the web-plies are pulled ahead for stripping the carbon-sheets; the lower feed-rolls being first released. The extent of the work-web carbon- 35 stripping movement may be determined by a gage. The clamps are then released and the web is rolled back to its new typing position, and the leading or typed set of forms is severed from the work-web.

According to another way of practicing my invention, a succession of perforated sets of forms constituting a multiple-ply work-web may be interleaved with ordinary rectangular carbon-sheets wider than the work-web and protruding a short distance from each side of the latter. Gage-pins may be provided on a telescoping gage-device, said pins engaging in the perforations of 40 the web, to help guide the work-web, as well as

determine the extent of its carbon-stripping movement after the carbon-sheets are clamped.

It will be seen as the description proceeds that my invention may be practiced with other kinds and arrangements of carbon-sheets than 50 those described above.

For feeding the carbon-interleaved work-web forward as a form is typed, usual lower feed-rolls co-operate with the platen and are thereafter released preparatory to pulling the work-web ahead for carbon-stripping purposes. It is a preferred feature of the present invention to provide a positive operative connection between the carbon-gripping clamps and the lower feed-rolls, which is effective to permit the latter to 65 be released only after the clamps have been operated, and is also effective to cause the feed-rolls to be thrown on before the clamps are released. The loose interleaved carbon-sheets are thus always secured against displacement, being 70 always held either by the rolls or by the clamps. It is a further feature of the invention to provide means for disabling the connection between the feed-rolls and the clamps, so that when desired the feed-rolls may be controlled by the usual 75 feed-roll-release lever without affecting the 80 clamps.

Other features and advantages will herein-after appear.

In the accompanying drawings, 85 Figure 1 is a fragmentary perspective view of an Underwood typewriting machine having my invention applied thereto. In this view, the work-web is shown in its position just before the carbon-stripping operation begins, the carbon-sheets being clamped and the feed-rolls released.

Figure 2 is a diagrammatic view of the structure shown in Figure 1, the work-web being shown at the end of the advance required for stripping the carbons.

Figure 3 is a fragmentary cross-sectional view, front to rear, through the structure shown in Figure 1. In this view is illustrated means for severing a typed set of forms after the work-web and carbons have been rolled back from the Figure 100 2 position, subsequent to the releasing of clamps from the carbons.

Figure 4 is a view similar to Figure 3, which illustrates an operative connection between the lower feed-rolls and the clamp for the carbon-sheets. This view shows how the clamps are made effective just before the feed-rolls are released.

Figure 5 is a view similar to Figure 4, show- 110

ing how the operative connection functions to release the feed-rolls.

Figure 6 is a perspective diagrammatic view, illustrating another form which my invention 5 may take, wherein means are disclosed for using ordinary rectangular carbon-sheets between plies of the web for manifolding purposes.

Figure 7 shows a diagrammatic cross-sectional view of a composite work-web having a special 10 carbon-sheet unit interleaved between the plies of the work-web which may be used in either the structure disclosed in Figure 1 or that disclosed in Figure 6.

Figure 8 is a flat or developed view of the fan- 15 folded carbon-sheet unit shown in Figure 7.

Figure 9 is a perspective view of a special carbon-sheet, which may be advantageously used.

The present invention is illustrated as applied to an Underwood standard typewriting machine, 20 in which types 10 strike against a platen 11 on a shaft 12, which is journaled in side plates 13 of a platen-frame 14. The platen may be rotated forwardly or rearwardly by finger-wheels 15 on the shaft 12, and may be line-spaced by usual 25 line-spacing instrumentalities (not shown). The platen-frame includes the usual plate or table 16. Rear and front feed-rolls 17 and 18 run upon the bottom of the platen. Instrumentalities for mounting the feed-rolls 17, 18 may include a cross- 30 rod 19 extending between the side plates 13, and levers 20 and 21 pivoted on the rod 19 for supporting shafts 22, 23 which carry the rear and front feed-rolls, respectively. The levers 20 and 21 have depending arms 24 and 25, respectively, which engage 35 against oppositely-disposed cam-flats 26 cut in a feed-roll-release shaft 27. Leaf-springs 28, supported by the cross-rod 19, urge the feed-rolls against the platen. To a crank-arm member 29, on the right end of the shaft 27, a link 30 is fastened loosely and extends upwardly to be 40 pivotally connected to a feed-roll-release lever 31. The construction of the parts described above may be the same as in a standard Underwood typewriting machine.

45 The link 30 is pivotally connected to the rear end of the release lever 31 by a shoulder-screw 32, whose inner end extends past the link 30 a short distance, for operation by a carbon-clamping lever 87.

50 An attachable frame 35 includes a right-hand and a left-hand bracket 36, each of which has a foot 37, which may be detachably fastened to platen-frame plates 38 by screws 39.

A standard 40 is provided on each bracket 36 55 at the forward end thereof. At the rear side of each standard, adjacent the upper end thereof, a lug 41 is provided, and a stiff cross-bar 42 may extend between the lugs and be fastened thereto. Inturned flange-members 43 may be formed on the standards 40 at the forward sides thereof, the flange-members extending below the tops of the side plates 13, to give a suitable range of adjustment to a web-severing knife 112 carried by the flanges. Threaded holes 44 are provided in each 60 flange-member 43 and are spaced apart preferably uniform distances along the flange, for use when adjusting the knife.

Each bracket 36 has an upwardly and rearwardly inclined rear arm 45, having a lug 46. A 70 stiff cross-bar 47 may extend between the lugs 46 and be fastened thereto.

For conducting a work-web 50, composed of a plurality of separate superposed plies 51, to the introductory side of the platen, a right-hand and 75 a left-hand guide-plate 52 are mounted on the

rear cross-bar 47, each plate being provided with a side-edge guide-flange 53. For laterally adjusting the guide-plates or chute-members 52, each is provided with two slots 54, positioned in recesses 55. Screws 56 may pass through the slots 80 and fasten the plates 52 to the cross-bar 47.

According to one form of the present invention, a front paper-table, generally designated as 60, includes a right-hand and a left-hand guide-plate 61, which are mounted for lateral adjustment on the cross-bar 42 by screws 56, which pass through elongated slots 62, in recesses 63, which may be like the recesses 55. A forwardly-extending side-edge guide-flange 65 for the work-web 50 is provided on each guide-plate 61 adjacent the top thereof. The guide-plates 52 and flanges 53 co-operate with the guide-plates 61 and flanges 65, forming a chute-like structure for the web 50.

For manifolding superposed form-sections 66 of the web 50, the leading end of the latter may be inserted and fed forwardly around the platen in the usual way until the lower end of the first set of forms rises above the printing line. A carbon-sheet 67 may now be interleaved, carbonized face down, between each two adjoining plies 51. Each carbon-sheet may have a tab 68 projecting on each side, adjacent its bottom edge. The width of the body-portion of each carbon-sheet 67 may be slightly narrower than 100 the width of the web 50, and the tabs protrude beyond the side edges of the work-web, usually about one-half inch.

A right-hand and a left-hand forwardly-extending integral side-edge guide-flange 70 110 forming a chute for the carbon-sheets 67 may be arranged on the front paper-table 60, adjacent the lower edge of the latter. The carbon-flanges are separated slightly more than the distance between the outer edges of the extensions 68, and may be arranged with respect to the side-edge guide-flanges for the work-web 50, whereby equal widths of the carbon-sheet extensions will project beyond the side edges of the work-web.

For gripping the carbon-sheets 67 by their lower portions at the delivery side of the platen, so that the work-web may be further advanced to strip the carbon-sheets, a clamp 73 is used, which clamps upon the carbon tabs or extensions 125 68. Each clamp may be pivoted on a screw 74 in the adjacent chute flange 70, and may have a rearwardly-extending arm 75, and is normally urged toward the paper-table 60 by a spring 76, which has one end fastened to the arm 75 and 130 the other end to a pin 77. Each clamp may have a pad 78 at its lower end provided with a rubber facing 79, and extending through a notch in the adjacent flange for engaging the adjacent carbon-sheet extension 68. The portion of each flange below the shoe is preferably bent outward to form a throat for the extensions.

Means for holding the clamps in raised positions may include a latching notch 80 in a rearwardly-extending arm 81. A latching arm 82 140 for each clamp 73 may be mounted for lateral adjustment on a horizontal rock-shaft 83, a pin 84 in the rear end of the arm having camming engagement with the arm 81 and locking engagement in the notch 80. The shaft 83 extends the 145 length of the platen and may be journaled in depending plates 85, riveted to the brackets 36. It will be noted from inspection of Figure 3 that when the pins 84 are seated in the notches 80, the pads 79 are maintained above the work- 150

- face of the paper-table 60 and permit free movement thereover of the carbons. The top edges of carbon-sheets 67, are arranged a short distance below the leading end of the first form. This permits the leading end of a typed set of forms to be grasped by the operative and pulled ahead for carbon-stripping purposes without affecting the interleaved carbon-sheets held stationary by the clamps 73.
- 10 Before the stripping movement of the work-web 50, the feed-rolls may be thrown off the platen by the usual feed-roll-release lever 31, but it is a feature of the present invention to employ means which are effective for releasing the feed-rolls 17, 18 just after making both of the normally released clamps 73 effective. By this arrangement an operation is saved, and also the carbon-sheets may always be controlled by either the feed-rolls, the bight of web-plies, or 15 the clamps, thus safeguarding the carbon-sheets against becoming disarranged.
- 15 The means for concomitantly controlling the feed-rolls 17, 18 the clamps 73 may include a handle or lever 87, fast on the shaft 83, and an operative connection between the lever 87 and the feed-roll-release lever 31. This connection may include a rear arm or extension 88 of the lever 87 having upper and lower jaws 90 and 91. Normally (Figure 3), the rear end of the arm 20 88 stands below the pivot-screw 32 in the rear end of the feed-roll-release lever 31. Jaw 91 may be wider than jaw 90. Downward pressure on a finger-piece 92 on the forward end of the lever 87 will swing the jaw 91 up to strike the screw and 25 raise it and the link 30, thereby releasing the feed-rolls 17 and 18. When rising, the jaw 90 passes by the screw or pin 32.
- 25 It can be seen from inspection of Figures 3 and 4 that the lever 87 moves idly for a time with respect to the feed-rolls. At the beginning of this movement of the lever 87, the pin 77 moves out of the latching notch 80 and permits the spring 76 to make the clamps 73 effective before the feed-rolls begin to move away from the platen.
- 30 It can be seen from inspection of Figure 5 that when the jaw 91 has raised the screw 32 enough to release the feed-rolls, the jaw 90 overlies the latter. Thereafter, the carbons having been stripped, the feed-rolls 17 and 18 can be moved from released positions to effective positions by returning the lever 87 from its foremost position, as indicated in the forward dot-and-dash representation of the lever in Figure 5, to its rearmost position. At the beginning of this returning 35 movement of the lever 87, its jaw 90 strikes down against the screw 32 and restores the feed-rolls to the platen during the first part of the stroke of lever 87. During this first part of the travel, the pins 84 in the arms 82 are idly swinging down 40 toward the arms 81, which they strike just after the feed-rolls engage the platen. During the remainder of the return or rearward travel of the lever 87, the pins 84 cam the arms 81 and the pads 79 counterclockwise until the pins 84 drop 45 into the locking notches 80, thereby holding the pads raised above the work-web 50. Also, during this last part of the travel of the lever, the jaw 90 will slip off the screw 32 and move down to its normal Figure 3 position. In the last-named 50 position of the jaws 90 and 91, they are entirely clear of the screw 32 or any other parts connected with the feed-roll-release lever 87, and the latter may be operated for releasing the feed-rolls without affecting the clamps. This feature permits 55 the feed-rolls to be released for truing the web-plies 51 and carbon-sheets 67 without causing interference by the pads 79.
- 60 For quickly determining the extent of stripping, a telescoping gage-bar, generally designated as 95, is provided, and is mounted on the cross-bar 42 between the guide plates 61. A midsection 96 of the cross-bar is offset, and a lower member 97 of the gage-bar is rigidly fastened to a spacer-block 98 by rivets 99, which also fasten the block rigidly to the cross-bar.
- 65 A carrier or truck-like member 100, may be slidably mounted on the member 97. An upwardly-extending slide-bar 101 is riveted to a boss portion 102 of the carrier 100, and may be slid along the member 97 until it is arrested by the upper end of 100 abutting against a stop-device 103, which may be constructed as a stop-strap. A rearwardly-bent lug 104 on the lower end of the bar-member 97 serves to stop the carrier 100 in its lowermost position.
- 70 A cross-bar 105 is adjustably fastened on the member 101 to be slid therealong by a clamping device 106, which may operate like the stop-device 103. The device 106, however, has only a single strap-arm 103a disposed behind the slide-bar member 101. A forwardly-extending gage-lug 107 is integrally joined to the top edge of the cross-bar 105, at each end thereof, in one form of my invention. The lower edge of the cross-bar 105 may be bent rearwardly, whereby the leading 75 edges of the work-web will slide easily up over the cross-bar against the lugs 107.
- 75 For convenience in gripping the leading edges of the work-web against the cross-bar, between an operative's thumb and fingers, a U-shaped base-member 108 may be riveted to the back of the cross-bar. A rearwardly-bent lug 109 on the upper end of the member 101 serves as a stop to prevent the cross-bar being displaced from the slide-bar 101.
- 80 The gage-lugs 107 on the adjustable cross-bar 105 are positioned above the pads 79, a distance equal to the depth of a form 66 when the gage-bar 95 is collapsed. The trailing ends of the carbon-sheets 67, in normal position, are approximately even with a weakened dividing line 110 provided between forms. When the leading edge of the work-web 50 is moved up against the lugs 107 after the form is typed, the trailing ends of the carbon-sheets, being pulled by friction of the 85 web-plies 51, will be approximately in line with the lower edges of the pads or clamps 79. The lever 87 is now operated for clamping the carbon-extensions 68, and the trailing ends of the carbon-sheets are held free of the platen, and no turn 90 or bend in the carbon-sheets interferes with the advance of the web-plies relative to the carbon-sheets.
- 90 As explained above, the feed-rolls 17 and 18 are now released, and the operative may grip the 95 leading edge of the web 50 by pinching it against the cross-bar 42 between the thumb and a finger of one hand, the thumb preferably engaging the web over the gage-bar 95, and the finger preferably engaging the base-member 108 (Figure 2).
- 95 When the gages and the work-web have been advanced until the gages are arrested by the carrier 100 abutting against the stop 103, the weakened line 110 between the typed set of forms and the next untyped set will stand a little above the leading edges of the carbon-sheets 67. It will be understood that the upper edges of the carbon-sheets will overlie the first writing line.
- 100 The finger-piece 92 is now swung up to the Figure 3 position, and the platen is reversely rotated.

until the first writing line of the leading untyped set of forms reaches printing position. In this position of the web 50, the dividing line 110 at the bottom of the typed set of forms will stand 5 along an edge 111 of the web-severing knife 112, which extends between the flanges 43 and may be adjustably mounted at different positions above the printing line by thumb-screws 113, which pass through holes in the ends of the knife 112 and 10 engage in the tapped holes 44 in the flanges 43. The typed forms may now be severed from the web 50, completing the cycle of operations.

In Figure 6, are provided ordinary rectangular carbon-sheets 120. Substantially the same 15 mechanism described hereinbefore may be employed, with only a few minor changes. The gage-lugs 107 on the cross-bar 105 are replaced by two gage-pins 121. Each set of forms 122 of a work-web 123 is provided with usual holes 124 20 for engagement with the pins 121. Provision of the pins and the holes makes the front side-edge gages for the work-web 123 unnecessary, since the pins not only determine the extent of the carbon-stripping advance of the web-plies and keep them 25 in registration with each other, but the pins also re-register the web-plies.

Side-edge guide-flanges 125 for laterally protruding portions of the carbon-sheets 120, which are wider than the web-plies, may be provided 30 and be substantially the same as the flanges 70, or they may extend upward a greater distance than the latter flanges. Clamping devices for the protruding carbon-sheet portions may be constructed and operated like the clamps 73 and may 35 include pads 79.

The width of the protruding portions 126 will usually be one-half inch or more. It will be understood that in the case of a thick work-web having an extra large number of plies, it may be 40 advisable to increase the width of the protruding portions of the carbon-sheets. It will be further understood that the distance from the inside edges of a pad or clamp 79 to the adjacent edges of the web-plies should always be enough to prevent 45 the upper carbon-sheets of the interleaved carbon-sheet assemblage being pulled tautly across the web-plies by downward pressure of the clamps. For the same reasons the width of the carbon-sheet extensions 68 should be slightly increased in cases where extra thick work-webs are 50 used.

In Figure 9 is shown a carbon-sheet 128 which may be advantageously used with the form of my invention illustrated in Figure 6. A lower edge strip 129 of the carbon-sheet 128 is folded up, which not only strengthens the lower edge against being torn by the advancing web-plies, but also 55 re-enforces the sheet where it has to stand the strain from the clamps 79 pressing the sheet down against the paper-table.

The Figure 6 form of my invention may be operated in substantially the same way as explained hereinbefore for the Figure 1 form of the invention, it being noted that after typing a set of forms, they are advanced and fastened on the pins 60 121 before the carbon-sheets are clamped.

In Figures 7 and 8 is shown a pack or assemblage 130 of carbon-sheets 131 which may be made from a single strip or sheet of paper 132 70 by carbonizing strip-sections, i. e., the sheets 131, alternately on the front and back of the strip and then fan-folding the latter to have all the carbonized surfaces facing in the same direction. Each sheet 131 has a carbonized portion 133 large enough for manifolding on an un-

derlying form (not shown) all data typed on a top web-ply 134 of a work-web 135. At each side of each carbonized portion 133, a plain, uncarbonized side-edge strip 136 of paper is left, and after the sheets are fan-folded and interleaved with the plies of the work-web 135 as illustrated in Figure 7, the strips provide a suitable area at each side of the work-web to be clamped in the way illustrated in Figure 6. It will be noted, however, that the carbon-pack 130 may also be used in the structure illustrated in Figure 1.

It can be seen that by having all the carbon-sheets of the carbon-pack 130 integrally connected as shown in Figures 7 and 8, each sheet 131 will help keep the other sheets of the pack from being disarrayed as the work or the pack is manipulated.

This application discloses improvements over my co-pending application No. 310,466, filed October 5, 1928.

Variations may be resorted to within the scope of the invention, and portions of the improvements may be used without others.

Having thus described my invention, I claim: 100

1. In a device of the class described, in combination, a platen around which may be fed a multiple-ply work-web interleaved with separate unattached carbon-sheets, the lower portions of said carbon-sheets extending outwardly from the side edges of said work-web, a paper-table at the delivery side of said platen, laterally adjustable side-edge guide-flanges on said paper-table for guiding said carbon-sheets, a clamp mounted on each of the flanges, for adjustment therewith, and at the delivery side of the platen and effective for gripping the protruding portions of said carbon-sheets at their lower ends, means for locking said clamps in released position, at all adjustments of said flanges and clamps, whereby the carbon-sheets may be fed under said clamps as said work-web is line-spaced, and adjustable means for releasing said clamps simultaneously at one operation, at any adjustment of the flanges and clamps. 110

2. In a typewriting machine having a round platen for manifolding a multiple-ply work-web interleaved with separate carbon-sheets wider than said work-web and protruding from both side edges thereof, the combination of a narrow 115

guide-chute for said web at the delivery side of said platen and above the point to which the carbon-sheets advance, to permit the advance of said carbon-sheets clear of the platen so that said carbon-sheets may be straightened above said platen, a wide guide-chute for said carbon-sheets at the delivery side of said platen, and clamping means on the lower end of said carbon-guide-chute for gripping the protruding portions of said carbon-sheets at their lower 125 ends, said clamping means including a clamp at each side of said work-web and means connecting said clamps for concomitant operation, an adjustable connection being provided between said clamps, whereby they may be operated with various widths of carbon-sheets, said carbon-guiding chute being adjustable for different widths of carbons, and said clamps being correspondingly adjustable. 130

3. In a typewriting machine having a platen 145 around which may be fed from the rear a form-bearing, multiple-ply work-web interleaved with loose carbon-sheets which are frictionally held between the web-plies and which have lateral extensions protruding from the sides of said web, 140

150

- the combination with releasable lower feed-rolls effective for feeding the work-web forward, of clamping instrumentalities for gripping said protruding extensions on each side of said web and holding said carbon-sheets stationary after they are frictionally moved clear of the platen by the advance of the work-web, mechanism for operating said clamping instrumentalities as a unit, and an operative connection between said mechanism and said feed-rolls, whereby either the latter or the clamps are always effective to hold the loose carbon-sheets under control against displacement relative to the web-plies. 5
4. The structure described in claim 3, having relatively adjustable chute-sections for said carbon-sheets, said clamps being correspondingly adjustable, and being operable at all adjustments by said clamp-operating mechanism, while the connection is maintained between the clamp-operating mechanism and the feed-rolls. 10
5. In a typewriting machine, the combination with a platen around which may be fed from the rear a multiple-ply work-web interleaved with loose carbon-sheets frictionally held between the plies of said work-web when bent around the platen, said carbon-sheets having lateral extensions protruding from the sides of said work-web, front and rear lower feed-rolls co-operating with said platen for feeding said carbon-interleaved work-web ahead, and a feed-roll-release lever, of instrumentalities for laterally guiding said carbon-sheets including a paper-table at the delivery side of said platen, clamps for gripping said carbon-sheet extensions against said paper-table on each side of said work-web, manually-operable devices for controlling said clamps as a unit, a connection between said devices and said release lever, whereby either the feed-rolls or the clamps are always in effective engagement with the carbon-sheets or the carbon-interleaved work-web, and means for disabling said connection, whereby said feed-rolls may be released by said release lever while said clamps remain released. 15
6. In a web-manifolding machine, the combination with a platen over which the web runs, of releasable feed-rolls to engage the web, a restraining device at the delivery side of the platen for engaging an interleaved carbon-set by its lower portion, means connected to said rolls for releasing them and to said restraining device for causing it to restrain the carbon-set, means for mechanically detaining said restraining device out of use, and means for releasing the rolls, at will, without bringing the restraining device into use. 20
7. In a web-manifolding machine, the combination with a platen over which the multiple-ply web runs with the interleaved carbons between the plies of web and protruding at the sides of the web, of clamps mounted at the delivery side of the platen and near thereto, in position to engage the protruding sides of the carbons at their bottom ends, a rock-shaft extending along the platen and having means to control said clamps, feed-rolls for the work-web, and means also controlled by said rock-shaft for releasing said feed-rolls. 25
8. In a web-manifolding machine, the combination with a platen over which the multiple-ply web runs with interleaved carbons between the plies of web and protruding at the sides of the web, of clamps mounted at the delivery side of the platen and near thereto, in position to engage the protruding sides of the carbons at their bottom ends, and a rock-shaft extending along the platen and having means to control said clamps, said machine having a chute for the web, including relatively adjustable side-edge guides, said clamp-controlling means being adjustable along said rock-shaft, and said clamps being adjustable with said guides. 30
9. In a web-manifolding machine, the combination with a platen over which the work-web runs, of guiding means for the work-web, other guiding means for interleaved carbons having protruding side-edge portions, clamps mounted at the delivery side of the platen and close thereto, to clamp the protruding edges at the bottoms of the carbons, a rock-shaft extending along the platen and having means to control said clamps, feed-rolls for the work-web, means also controlled by said rock-shaft for releasing said feed-rolls, and a key for releasing said feed-rolls independently of said clamps. 35
10. In a web-manifolding machine, the combination with a platen over which the web runs, and feed-rolls for the platen, of a feed-roll releasing train, clamps mounted at the delivery side of the platen, and a rock-shaft extending along the platen and having means to control said clamps, including means mounted upon said rock-shaft to hold said clamps mechanically in released positions, an arm being provided upon said rock-shaft normally out of range of movement of the feed-roll releasing train but movable into engagement with said train to release the feed-rolls when the clamps move to carbon-clamping positions. 40
11. A typewriting machine having types and a revoluble platen, and having provision for permitting a relative manual stripping operation between (1) a set of loose carbon-sheets and (2) a set of work-sheets in the form of plies of work-web having a crosswise relation to the carbon-sheets, the latter being made substantially over-wide and projecting at the side of the work-sheets, said work-sheets projecting at the top of the set of carbons, and a releasable projection-engaging stripper-clamp mounted at the delivery side of the platen and having a member by which one set of sheets is clamped and held stationary while the other set of sheets is grasped by the operator and stripped relatively to the clamped set, the machine having a general work-support upon which the unclamped set of sheets is supported with their edges clear for manipulation. 45
12. A typewriting machine having types and a revoluble platen, and having provision for permitting a relative manual stripping operation between (1) a set of loose carbon-sheets and (2) a set of work-sheets in the form of plies of work-web having a crosswise relation to the carbon-sheets, the latter being made substantially over-wide and projecting at the side of the work-sheets, said work-sheets projecting at the top of the set of carbons, a releasable projection-engaging stripper-clamp mounted at the delivery side of the platen and having a member by which one set of sheets is clamped and held stationary while the other set of sheets is grasped by the operator and stripped relatively to the clamped set, the machine having a general work-support upon which the unclamped set of sheets is supported with their edges clear for manipulation, and a gage to which the leading edges of the web-plies are brought, whereby the typed form is located a form's length above the platen. 50
